UNITED STATES PATENT OFFICE.

JOHN AMES SHERMAN AND JOHN EDWARD SHERMAN, OF WORCESTER, MASSACHUSETTS.

PACKAGE FOR PAPER DRINKING-CUPS.

1,222,566.

Specification of Letters Patent. Patented Apr. 10, 1917.

Application filed September 1, 1914. Serial No. 859,704.

To all whom it may concern:

Be it known that we, JOHN A. SHERMAN and JOHN EDWARD SHERMAN, both of Worcester, in the county of Worcester and 5 State of Massachusetts, citizens of the United States, have invented a new, useful, and Improved Package for Paper Drinking-Cups, of which the following is a specification.

10 In the present demand for sanitary drinking cups so-called, the demand has also arisen for containers in which they are deposited and from which they are withdrawn to be used. Such containers, so far as we 15 know, are fixtures attached to the wall of the building or car which are refilled from time to time as occasion requires. The cups come in bulk, so to speak, from the manufacturer, and when the shipping box has been opened 20 the cups are taken by hand by the janitor or railway porter or brakeman and are inserted in the container which is then closed. This arrangement is hardly sanitary because the cups are thus handled in the natural order 25 of business by men whose usual work is not clean and who could not be expected to handle them with clean hands. Moreover, unless the container is constantly cleaned out, after it has been in use for a time it collects dirt and germs which are collected on 30 the cups themselves.

The whole scheme, therefore, though in its conception a sanitary measure does not necessarily fulfil its purpose.

35 Our invention is a serving container or package which is filled with cups and sealed at the factory where the cups are made and requires no manipulation except unpacking and hanging on the wall so that the cups 40 are not touched after they leave the factory until put into actual use.

When emptied the container may be replaced by another and thrown away because of its cheapness. It is preferably made of 45 cheap strawboard and after being filled is covered and sealed with more or less ornamental paper which may carry advertisements if desired—so that its cost its infinitesimal.

50 Our invention will be understood by reference to the drawings, in which—

Figure 1 is a vertical section of our package attached to a wall, taken on line 1—1 of Fig. 2.

55 Fig. 2 is a front elevation thereof.

Fig. 3 is a vertical section on line 3—3 of Fig. 1 of an empty container, and

Fig. 4 is an elevation of a convenient form of attaching hook attached to the wall.

Fig. 5 is a detail.

A is the wall or other support to which is attached the hook by which the package is supported. This hook may be of any convenient shape but preferably consists of a plate B provided with screw holes for screws 60 b by which it is attached to its support and a tongue B¹ which is offset about the thickness of the material of which the container is made. This tongue has preferably a lip b¹ cut from it and projecting downward. 70 This lip does not interfere with the hanging of the container on the hook but renders it difficult to remove it.

The container is preferably made of a size in horizontal section to receive the cups D 75 folded flat and is of sufficient height to hold say 250 cups. It is shown at C and is made of a single thickness of pasteboard, strawboard, or the like, in the nature of a box into which the cups are packed. It is then 80 closed and covered and sealed with paper so that the contents as a whole cannot be handled and the cups can only be removed one by one as now to be described.

The bottom or floor of the container is 85 provided with a cup support in the form of a strip of wood or other material c, preferably a little thicker at the rear than at the front so that the cups will slant forward somewhat from the rear to the front. At the 90 front lower edge of the container we provide a slot c¹ which is the entire width of the container and through which the cups may be withdrawn one by one.

From Fig. 2 it will be seen that the cups are raised by the strip c above the level of the slot c¹ and to enable the lower cup to be withdrawn we provide notches E, F, one for the finger and the other for the thumb so that the lower cup may be grasped and 100 pulled down and out through the slot c¹, allowing the next cup above it to take its place.

Owing to the thinness of the paper with which the container is covered it cannot be 105 shown in the drawing except by a line which would be confused with the outer line of the strawboard and hence no attempt has been made to show it. It will be understood, however, that the entire container is cov- 110

ered with paper so that the paper seals the container except at the slot c^1 and notches E, F .

To support the container on the hook B , B^1 we cut a slit c^2 in the rear of the container through which the tongue B^1 of the hook may enter the container, the container resting on the offset between B and B^1 and to prevent the tongue from engaging the cups 10 we preferably attach to the inside of the container at g the protecting strip G of strawboard or the like which lies between the pile of cups and the slit c^2 so that when the tongue B^1 enters through the slit c^2 it will 15 engage the strip G and slide upward thereon until the container rests on the offset. Thus the cups are prevented from injury and the upper cups can never engage the hook and so accidentally be prevented from 20 settling into place as the lower cups are withdrawn.

For shipping we provide an ordinary cover to close the slotted end of the container. Such a cover is indicated by dotted 25 lines at H , Fig. 2, and when the container is put into use the cover is thrown away. The advantages of our container will be apparent. The sealing of the cups at the factory is practically essential to the sanitary success 30 of the use of individual cups as above explained and this requires the use of a container strong enough to maintain its shape and position when hung up and yet of sufficiently low cost to be thrown away when 35 empty, for railroad companies and other buyers will not go to the trouble and expense of returning containers to be refilled. It will be noted that the strip c holds the lower cup out of register with the slot so that 40 when the last cups are left in the container they cannot slide out. Other means of so retaining the cups will suggest themselves to those skilled in the art.

What we claim as our invention is:

1. The device above described comprising 45 a container having a slot extending substantially the entire width thereof along one of its bottom edges and notches in each wall adjacent said slot, said container being provided with means to support articles out of 50 register with said slot and in register with said notches.

2. The device above described comprising a sealed container having vertical sides and a slot along one of its bottom edges, cups 55 located in said container, means for holding said cups out of register with said slot and in slanted relation, comprising a floor extending from the rear edge of said container nearly to its forward edge, said floor 60 being thicker at its rear edge than at its forward edge whereby the lowermost cups will engage the front vertical wall of said container above said slot, and notches in the edges of said slot whereby the lowermost of 65 said cups may be grasped, pulled into register with said slot and withdrawn there-through.

3. The device above described comprising 70 a sealed container made of destructible material, having a slot along one of its bottom edges and notches in each wall adjacent to said slot, and a cup support on the inner side of the bottom thereof located to deliver 75 cups to said slot, said container being provided with a slit in its rear wall adapted to receive a supporting means, in combination with a protecting strip attached to the rear inner wall of said container and loosely covering said slit.

JOHN AMES SHERMAN.
JOHN EDWARD SHERMAN.
